Patented Apr. 24, 1917.

UNITED STATES PATENT OFFICE.

ISAAC POMPER, OF NEW YORK, N. Y.

SHOPPING-BAG.

1,223,420.

Specification of Letters Patent. Patented Apr. 24, 1917.

Application filed December 26, 1916. Serial No. 138,892.

To all whom it may concern:

Be it known that I, ISAAC POMPER, a subject of the Emperor of Austria-Hungary, residing at New York, in the county of New York and State of New York, have invented 5 certain new and useful Improvements in Shopping-Bags, of which the following is a specification.

The present invention relates to shopping 10 bags and particularly to bags which have flexible or collapsible sides and has for its object to provide a construction which will be more durable than bags constructed according to my Patent No. 1,189,480.

15 Another object of my invention is to provide a bag which at its opening or mouth portion will be reinforced by means sufficiently stiff to prevent the bag from sagging out of shape, but which will be sufficiently 20 flexible to bend if packages or other articles project from the top of the bag.

A further object is to so fasten the handles or grips to the bag that the material of the bag and of the stiffening means will not 25 be weakened and the ends of the handles will be prevented from bending or curling up.

30 My invention will be fully understood by reference to the accompanying drawing, in which similar characters denote corresponding parts and in which Figure 1 is a perspective view of my improved bag with the sides shown stretched flatly; Fig. 2 is an end view partly in section as seen in the direction of 35 the arrows 2—2 in Fig. 1, of which the lower part is shown torn away; Fig. 3 is a similar view as seen in the direction of the arrows of line 3—3 of Fig. 1 with the lower part torn off and Fig. 4 is a cross section of a 40 modified construction.

The bag consists of the flexible sides *a* which are made of cloth, oilcloth, or other suitable flexible material and end gussets *b* of similar material, so that when not in use 45 the bag can be folded up or rolled together. The sides may preferably be extended to project beyond the upper edges of the gussets and to serve to close around the opening of the bag when the latter after being filled 50 with packages or other articles is carried by means of the handles *c*. The upper ends of the bag are stiffened by strips of material which while stiff enough to prevent the top of the bag from sagging out of shape, will 55 be sufficiently flexible to bend if packages or

other articles project at some portion of the top of the bag.

As stiffening means I prefer to use card board, but any other suitable semi-rigid and light material may be employed. According 60 to Figs. 1-3 the strips *d* which are made of a length substantially equal to the length of the sides of the bag, are flat against the inner face of the sides and held in position by hem pieces *e* which may be, as shown, integral with the material from which the sides of the bag are made or may be separate pieces and which form pockets *f* in which the members *d* loosely rest.

65 In my former Patent No. 1,189,480, the handles or grips *c* have been attached by passing the looped ends of the latter through openings cut through the upper parts of the sides of the bag and reinforced by metal eyelets. But such construction has proved 70 defective or objectionable in the following respects. When carrying the bag filled with heavy articles, the weight exerts a strong pull on the material, in consequence of which the edges around the openings slip 75 out from the metal eyelets, which leads to further damage to the bag. Furthermore, the material of the bag being *per se* not very strong becomes greatly weakened by cutting 80 out the openings for the handles. Similarly 85 the reinforcing strips which are to stiffen the upper ends of the bag fail in the object when holes are punched through them.

85 To obviate all these objections, the handles *c* according to this invention, are attached to the sides of the bag as follows:

90 Instead of forming loops at the ends of the handles, the ends *c'* are placed flat against and are attached to the outer faces 95 of the sides of the bag. To simplify the construction, instead of sewing on the handles, the same are riveted and the rivets *c''* are passed also through the edges of the hem pieces *e* which hold the reinforcing strips *d* in place.

100 But inasmuch as the rivets *c''* leave the edges of the ends of the handles free, the edges are apt to curl up or be caught by some objects in their vicinity, which may result in damage to the bag. To obviate this the ends *c'* of the grips or handles are concealed in pockets *g* formed by pieces *g* of flexible material which are placed flat against the outer faces of the sides of the bag so as to cover the upper parts thereof. 110

These pieces may be secured to the bag along their edges by stitches g' . Opposite the ends c' of the grips and intermediate between their longitudinal edges the pieces 5 g are cut out to form openings g^3 through which the ends c' can freely project outwardly from the pockets. The edges of the openings g^3 are reinforced by metal eyelets h . To strengthen the bag at the points 10 of attachment of the ends of the grips thereto, the rivets c^3 are preferably passed through the pieces g . Thus the latter will not only serve to shield the ends c' of the grips, but also as auxiliary reinforcing 15 means for the bag.

To further simplify the construction of the bag, the stiffening strips d may be entirely dispensed with and instead the pieces 20 g be made of some heavier material which will be semi-rigid.

In the modification shown in Fig. 4 the strips d are contained in pockets j formed by pieces k of flexible material which like the pieces g are placed on the outer faces of 25 the sides of the bag and suitably attached thereto. The pieces k have openings g^3 reinforced by eyelets h through which the ends c' of the handles project outwardly from the pockets j . The pieces are attached 30 by rivets c^3 .

It is obvious that other modifications may be made in the construction of the bag without departing from the principle of my invention and therefore I do not wish to be 35 understood as limiting myself to the details shown and described.

What I claim and desire to secure by Letters Patent is:

1. A hand bag having flexible sides and 40 an open top, stiffening strips of semi-rigid material along the upper parts of said sides, handles having their ends placed flat against and attached to said sides and shields of flexible material for the said ends, said shields having openings through which 45 said ends project outwardly from beneath said shields and eyelets reinforcing the edges of said openings.

2. A hand bag having flexible sides and 50 an open top, handles having their ends placed flat against and attached to the outer faces of said sides, stiffening strips of semi-rigid material for the upper parts of said sides and pieces of flexible material lying in 55 planes parallel to said sides and on the outer faces thereof and serving to hold said stiffening strips in place and also to shield the ends of said handles.

3. A hand bag having flexible sides and an open top, handles having their ends 60 placed flat against and attached to the outer faces of said sides, pieces of flexible material lying on the outer faces of and in planes parallel to said sides and formed with pockets and stiffening strips of semi-rigid 65 material in said pockets, said pieces serving also as shields for the ends of said handles.

4. A hand bag having flexible sides and an open top, handles having their ends 70 placed flat against and attached to the outer faces of said sides, perforated pieces of flexible material lying on the outer faces of and in planes parallel to the said sides and formed with pockets, stiffening strips 75 of semi-rigid material extending substantially the length of and over the upper parts of said sides and contained in said pockets, said ends of the handles projecting outwardly from beneath said pieces 80 through the perforations thereof.

5. A flexible hand bag having an open top, handles having their ends placed flat against the outer faces of said bag, pieces of flexible material fixed and lying in planes 85 parallel to the said outer faces and serving to shield the ends of said handles, said pieces having openings intermediate between their longitudinal edges, through which openings the ends of said handles 90 freely project outwardly from beneath said pieces and rivets immediately below and above said openings for fixing the ends of said handles, said rivets being passed both through the said shielding pieces and material of the bag.

6. A hand bag having handles, the ends of which are placed flat against the outer faces of the sides thereof, pieces of flexible material fixed and lying in planes parallel 100 to the said outer faces and serving to shield the ends of said handles and to reinforce the bag, said pieces having openings through which the ends of said handles freely project outwardly from beneath said 105 pieces and rivets passed through said shielding pieces and material of the bag below and above said openings for fixing the ends of said handles.

In testimony whereof I affix my signature 110 in presence of two witnesses.

ISAK POMPER.
